UNITED STATES PATENT OFFICE

168,935

BEVERAGE COOLER

Robert M. Hallock, Atlanta, Ga.

Application June 16, 1952, Serial No. 20,217

Term of patent 14 years

(Cl. D67—4)

To all whom it may concern:

Be it known that I, Robert M. Hallock, a citizen of the United States of America, residing at Atlanta, in the county of Fulton and State of Georgia, have invented a new, original, and ornamental Design for a Beverage Cooler, of which the following is a specification, reference being had to the accompanying drawing, forming a part thereof.

In the drawing:

I claim:

The ornamental design for a beverage cooler, as shown.

ROBERT M. HALLOCK.
